UNITED STATES PATENT OFFICE.

HENRY EISELE, OF DECATUR, ILLINOIS.

QUARTERING DEVICE FOR LOCOMOTIVE WHEELS.

Application filed May 28, 1924. Serial No. 716,355.

To all whom it may concern:

Be it known that I, HENRY EISELE, a citizen of the United States, a resident of Decatur, in the county of Macon and State of Illinois, have invented a certain new and useful Quartering Device for Locomotive Wheels, of which the following is a specification.

The invention relates to improvements in devices for quartering driving wheels of locomotives and the like, to provide a simple, practical and efficient device of strong and comparatively inexpensive construction adapted to be readily applied to the driving wheels of an axle of a locomotive, and capable of ready adjustment to suit the diameter of the wheel and the depth of the center opening and of enabling the relative angular position of the wrist pins to be easily, quickly and accurately determined.

With the present style of locomotive driving wheel quartering devices, it is impossible to read the gauge in variations of degrees and it is an object of the present invention to provide a locomotive driving wheel quartering device adapted, should the readings of the device when applied to the driving wheels of an axle not exactly total 90° to indicate the amount of the variation in degrees and fractions of degrees.

To the accomplishment of the foregoing, and such other objects as may hereinafter appear, my invention consists in the construction, combination and arrangement of parts hereinafter described and then sought to be defined in the appended claims, reference being had to the accompanying drawings forming a part hereof and which show, merely for the purpose of illustrative disclosure, a preferred embodiment of my invention, it being expressly understood, however, that variations may be made in practice within the scope of the claims without digressing from my inventive idea.

45 In the drawings:

Figure 1 represents an elevational view of a locomotive drive wheel with a device constructed according to my invention shown in use.

50 Figure 2 is an enlarged front elevation of a device constructed according to my invention.

Figure 3 is a central longitudinal sectional view taken substantially on the line 3—3 of Fig. 2.

55 Figure 4 is an enlarged detail reverse plan

view illustrating the construction of the sliding head which carries the axle engaging member.

Figure 5 is a front elevation of a locomotive drive wheel quartering device illustrating another form of the invention, in which a bubble tube leveling device is substituted for a pointer.

Figure 6 is a similar view illustrating another form of the invention in which the indicating member is in the form of a weighted graduated dial.

Referring particularly to Figures 1 to 4 inclusive of the drawings, 1 designates a driving wheel having a wrist pin 2, and mounted on an axle 3 which is provided with the usual center hole. In the case of locomotives, the wrist pins on the opposite wheels of an axle are maintained at an angle of 90° relative to each other. This relative position may be disturbed through wear and tear of operation and the device of the present invention will quickly indicate whether or not the wheels are properly positioned. The device is also adapted for testing the position of the wheels when renewing the axle or a wheel or wheels and in pressing the same on the ends of the axle.

The device comprises in its construction, 55 a squared bar 4, provided at its upper end with integral angularly disposed arms 5 forming a forked or V-shaped member or yoke having the edge 6 at the junction of the said arms 5 adapted to fit against the 60 wrist pin 2 in positioning the device on a wheel. Secured to the bar 4, which constitutes the body of the device, is a circular base plate 7, preferably attached to the upper portion of a bar 4 by screws 8, but the 65 base plate which constitutes the back of the indicating means may be made rigid with the bar 4 in any other desired manner. Mounted on the circular relatively fixed member 7, is a rotary member consisting of 70 an adjustable wheel composed of inner and outer circular sections 9 and 10 and secured together by screws 11 arranged at spaced points adjacent the peripheries of the inner and outer sections of the rotary member. 75 The inner section 9, which is circular, consists of a flat disk constituting a dial and provided with a central inwardly or rearwardly projecting cylindrical boss 12, constituting a journal and fitted in a central bearing opening 13 in the fixed circular member 7, as clearly illustrated in Fig. 3 of

100 105 110

the drawings. The central journal 12 is provided with a reduced threaded portion 14 on which is mounted a washer 15, a nut 16 which engages the washer and maintains the tension adjustment of the same against the central bearing portion 17, of the fixed member 7, and a lock nut 16^a which locks the adjustment of nut 16. The washer 15 which is assembled over the threaded portion 14 is locked in position against rotary movement by pin or key. The bearing portion 17, is arranged at the rear face of the fixed member 7 and the latter is provided at its front face with central and circumferential bearing portions 18 and 19, which receive corresponding bearing portions 20 and 21 of the inner section 9 of the rotary adjustable member. The relatively fixed member 7 and the inner section 9 of the rotary member are recessed or cut away to provide a clearance 21^a, between the central and circumferential bearing portions for reducing friction to a minimum. The inner section 9 of the adjustable rotary member is provided with an inwardly extending peripheral flange 23 which fits in a corresponding annular recess 24 of the said rib 22. The said inner section 9, extends circumferentially beyond the outer section and is bevelled at the outer face of the circumferential portion at 25, the bevelled face being graduated to provide a scale. The graduations of the scale preferably start at zero and run to 90° in each direction and then extend again to zero, two series of such graduations being thus provided so that the dial is divided into quadrants of 90° each. This scale of the rotary adjustable member cooperates with a hair line 26 of a hand or pointer 27, and also with a vernier scale 28 mounted on the relatively fixed member 7 and preferably located at the bottom thereof as clearly illustrated in Fig. 1 of the drawings.

The indicating hand or pointer which is located within the rotary adjustable member is provided with a weighted lower portion 29 and is mounted on cone pivots 30 and 31 carried by the inner and outer sections 9 and 10 of the rotary adjustable member. The cone pivot 30 which consists of a head and a reduced shank is mounted in a central portion 32, in the inner section 9 which is counter-bored to receive the head of the cone pivot 30. The head of the cone pivot 30 is seated against the shoulder formed by the counter-bore of the inner section 9 of the rotary adjustable member. The cone point 31 is mounted in a central bore 33 of outer section 10 which is counterbored and threaded at the outer portion of the said bore 33 to receive the threaded end of cone pivot 31, the thread on cone pivot 31, which is provided as a means of adjustment, is locked in position by the nut 34. The indicating hand or pointer is provided with central bearings at its inner and outer face preferably formed by a small bore extending entirely through the hand or pointer and slightly enlarged at the terminals to receive the cone pivots. By this construction, the indicating hand or pointer is exceedingly sensitive and binding of the same within the rotary adjustable member is effectually prevented. Also the pivots may be readily adjusted to compensate for any wear of the parts. The outer section is provided with a side aperture 35 located at the upper portion of the said outer section and adapted to uncover the upper end of the indicating hand or pointer and the hair line 26, in any position the hand or pointer may assume by reason of the position of the wrist pin of a driving wheel. The rotary adjustable member is provided with a hair line 36, which is adapted to be brought into register or alignment with the hair line 26 of the indicating arm or pointer and a reading of the quartering gauge is taken from the bottom of the adjustable member, the vernier gauge 28 being adapted to afford a division of degrees into tenths as will be readily understood.

The bar 4 receives an adjustable block 37 carrying an axle engaging member 38 and provided with an opening 39 of substantially rectangular form to present smooth side faces or walls to the side faces of the bar 4 and cut away at the corners at 40 and 41, to prevent the corners of the bar from contacting with the walls of the opening of the block. This construction by providing corners clearances, enables the block to slide on the bar 4 with a minimum amount of friction. The block is provided at the front with a set screw 42 threaded into the block and arranged to engage the bar 4, for clamping the slidable block 37 in its adjustment. The block is provided at its upper portion with spaced aligned guides 43 and 44, formed integral with the block and having aligned openings for the reception of spaced parallel rods 45 which constitute a part of the axle engaging member 38 and which are connected at one end with the head of the same. The rods 45 are mounted at opposite sides of the bar 4 and they firmly support the axle engaging head or portion 38 in a central position with relation to the axis on the bar 4. The guides 43 and 44 project laterally from the block and the guides 44 are split at the bottom by means of a kerf 46 to form resilient clamps for engaging the rods 45 to maintain the axle engaging member in its adjustment. The block is provided at the guides 44 with a transverse opening 47 receiving a clamping screw 48 provided at one end with the head and threaded at the other end to engage a threaded part of the opening 47.

The opening 47 is threaded at one end beyond one of the kerfs 46 and the head of the screw engages the guide 44 at the outer side of the other kerf 46. By this construction, the rods 45 may be clamped in their adjustment. The axle engaging member 38 which fits in the center opening of the axle, consists of a ball head and the said rods 45. A head of the axle engaging member is preferably rounded or semi-spherical at the outer portion and has a polygonal inner portion with which the rods 45 are connected. By adjusting the screws 42 and 48, the axle engaging device may be readily arranged at the desired distance from the yoke to fit in the center opening of the axle and the axle engaging device may also be moved inwardly and outwardly with respect to the bar 4 to correspond with the depth of the center opening of the axle.

The indicating means consisting of the pivoted pointer or hand 27 may be varied in construction and instead of employing a hand as shown in Figs. 1 to 4 inclusive, the rotary adjustable device may be equipped with a level 49 having a bubble tube as illustrated in Fig. 5 and if desired the indicating means may consist of a disk 50 weighted at the lower portion at 51 for maintaining its indicating means in a vertical position. In each instance the readings are taken at the bottom of the rotary adjustable member and vernier scales will in practice be provided for each quartering gauge.

In the use of the quartering gauge, the device is applied to one of the wheels of an axle by fitting the axle engaging member in the central opening of the axle and the yoke against the wrist pin of the drive wheel and the reading is taken at the bottom of the rotary adjustable member. The device is then transferred to the other driving wheel of the axle and the position of the wrist pin is found in the same manner and if the sum of two readings is 90°, the wrist pins will be in proper position, but if there should be any variation between 90° and the actual position of the wrist pins, the variation will be indicated in degrees and fractions of a degree by the vernier scale.

What I claim is:—

1. A device of the class described comprising a body provided at one end with a wrist pin receiving yoke, an axle engaging member carried by the body at the other end thereof, an indicating device comprising a member stationary relative to said body, a relatively rotary member mounted on the relatively stationary member for rotary adjustment and provided with graduations associated with the stationary member, and indicating means mounted on the adjustable member and cooperating therewith.

2. A device of the class described com-

prising a body provided at one end with a wrist pin receiving yoke, an axle engaging member carried by the body at the other end thereof, an indicating device comprising a member stationary relative to said body, a relatively rotary member mounted on the relatively stationary member for rotary adjustment and provided with graduations associated with the stationary member, and a pivoted indicating element mounted on the adjustable member and having a weighted portion for maintaining the indicating member in a predetermined position.

3. A device of the class described comprising a body provided at one end with a wrist pin receiving yoke, an axle engaging member carried by the body at the other end thereof, an indicating device comprising a member stationary relative to said body, a relatively rotary member mounted on the relatively stationary member for rotary adjustment and provided with graduations associated with the stationary member, and an indicating hand mounted on the adjustable member and having a weighted portion for maintaining the hand in a perpendicular position.

4. A device of the class described comprising a body provided at one end with a wrist pin receiving yoke, an axle engaging member carried by the body at the other end thereof, an indicating device comprising a member stationary relative to said body, a relatively rotary member mounted on the relatively stationary member for rotary adjustment and provided with graduations associated with the stationary member, and an indicating hand pivotally mounted within the adjustable member, the latter being provided with a sight aperture and adjustable for indicating the position of the indicating member through the sight aperture.

5. A device of the class described comprising a body provided at one end with a yoke, an axle engaging member mounted on the body at the other end thereof, an indicating mechanism carried by the body adjacent the yoke and comprising a member stationary relative to said body, a rotary adjustable member mounted on the fixed member and composed of inner and outer sections secured together, the outer section being provided with a sight aperture and a pivotally mounted indicating member contained within the adjustable member and adapted to be exposed through the aperture.

6. A device of the class described including a body, a yoke located at one end of the body to engage a wrist pin, an axle engaging member carried by the other end of the body and indicating mechanism mounted on the body adjacent the said yoke and comprising a relatively fixed member

stationary relative to said body, a rotary adjustable member of circular form mounted on the fixed member provided with peripheral graduations, a vernier scale carried by the stationary member and associated with the said graduations, and a levelling device mounted on the adjustable member.

7. A device of the class described including a body, a yoke located at one end of the body to engage a wrist pin, an axle engaging member carried by the other end of the body and indicating mechanism mounted on the body adjacent the said yoke and comprising a relatively fixed member stationary relative to said body, a rotary adjustable member of circular form mounted on the fixed member provided with peripheral graduations, a vernier scale carried by the stationary member and associated with the said graduations, and a levelling device consisting of a pivoted member mounted within the adjustable member.

8. A device of the class described including a body provided at one end with wrist pin receiving means and having an axle engaging member at the other end, a relatively fixed member mounted on the body, a rotary adjustable member composed of inner and outer sections, the inner section being pivoted to the fixed member and provided with a projecting circumferential portion and having an annular rim thereat, the outer section being flanged and fitting the rib of the inner member and secured to the same, and indicating means mounted within the adjustable member.

9. A device of the class described comprising a bar provided at one end with wrist pin receiving means, a block slideable on the bar and having means for securing it in its adjustment, an axle engaging member having a head to fit in the center opening of an axle and mounted for slideable movement on the block at right angles to the axis of the bar to extend to the bottom of the axle opening, means for securing the axle engaging member in its adjustment, and indicating means carried by the bar.

10. A device of the class described comprising a bar provided at one end with wrist pin receiving means, a block slideable on the bar and having means for engaging the same, to secure it in its adjustment, an axle engaging member having spaced parallel rods located at opposite sides of the bar and slideable on the block at right angles to the axis of the bar to extend the axle engaging member to the bottom of the central opening in an axle, and means for securing the rods in their adjustment, and indicating means carried by the bar.

11. A device of the class described comprising a bar provided at one end with wrist pin receiving means, a block slideable on the bar and having means for engaging the same, to secure it in its adjustment, a block slideable on the bar and having means for securing it in its adjustment, said block being provided with spaced guides located at opposite sides of the bar, an axle engaging member comprising a head adapted to fit in the center opening of an axle and spaced circular rods connected with the head and arranged in the guides of the block, means for clamping the rods in their adjustment, and indicating means carried by the bar.

12. A device of the class described comprising a bar provided at one end with wrist pin receiving means, a block slideable on the bar and having means for engaging the same, to secure it in its adjustment, a block slideable on the bar and having means for securing it in its adjustment, said block being provided with spaced guides located at opposite sides of the bar, an axle engaging member comprising a head adapted to fit in the center opening of an axle and spaced circular rods connected with the head and arranged in the guides of the block, said block having split portions adjacent the said guides and a clamping screw for compressing the split portions to clamp the rods.

13. A device of the class described including a bar, wrist pin receiving means located at one end of the bar, a block slideable on the bar and provided with spaced guides and having kerfs located adjacent the guides, said block being provided with an opening intersected by the kerfs, an axle engaging member having spaced rods mounted in the guides and a clamping screw arranged in the said opening and adapted to bind the rods in the guides.

14. A device of the class described including a bar, wrist pin receiving means located at one end of the bar, a block slideable on the bar and having means for securing it in its adjustment, said block being provided with spaced aligned guides arranged in pairs one member of each pair having a kerf, an opening being formed in the block intersecting the said kerfs, an axle engaging member having spaced parallel rods slideable in the said guides, and means mounted in the said opening for compressing the guides having the kerfs for clamping the rods to secure the axle engaging member in its adjustment.

In testimony that I claim the foregoing I have hereunto set my hand this 24th day of May, 1924.

HENRY EISELE.
